ADJUSTABLE SEAT

John M. Dorton, Bonner Springs, Kans.

Application August 23, 1934, Serial No. 741,114

5 Claims. (CL 155—32)

My invention relates to adjustable seats and one object is to provide a device of this character which is well adapted for use in the cabs of locomotives.

One feature of the invention resides in the provision of resilient legs adapted to absorb to a large degree the lateral swaying of the locomotive when in operation, so that the engineer will suffer no ill effects from such swaying when occupying the seat of the device.

Another feature resides in the provision of a stationary frame upon which the seat and the back of the device may be supported at different elevations to suit the convenience of users of different heights. The seat and the back are also hingedly connected so that the seat may be swung upwardly or downwardly and the back forwardly or backwardly.

With slight modifications the device may also be used to advantage in other vehicles such as busses, steam railway and electric cars, automobiles, and the like, and in public institutions such as churches, theaters, etc.

Other features will hereinafter appear and in order that the invention may be fully understood, reference will now be had to the accompanying drawings, in which:

Fig. 1 is a perspective view of one form of the device with the cushion removed.

Fig. 2 is a vertical sectional view of the device with cushioning means in position thereon.

Fig. 3 is a sectional view of the device with the cushioning means in elevation.

Fig. 4 is a detail partly in section of mechanism for adjusting the seat frame or the back frame of the device.

Fig. 5 is a cross section on line 5—5 of Fig. 4.

Fig. 6 is a detail of two spiral gears forming part of the mechanism disclosed by Figs. 4 and 5.

Fig. 7 is an enlarged cross sectional view on line 7—7 of Fig. 1.

Fig. 8 is a perspective view of a modified form of the seat and back frames.

Fig. 9 is a side elevation partly in section showing the seat and back frames and a modified form of cushion.

Fig. 10 is a broken detail view showing certain parts employed in carrying out the invention.

Fig. 11 is a fragmentary view of a portion of a woven wire strip, a plurality of which are embodied in the cushioning means.

Referring more particularly to the parts shown by Figs. 1 to 7, inclusive, 2 designates a main frame comprising a pair of upright members 4 held in spaced relation to each other by upper

and lower transverse members 6 and 8, respectively. The upright members 4 consist preferably of flat spring metal so that legs 10 forming the lower portion of said upright members 4 may sway laterally for a purpose hereinafter pointed out. The resilient legs 10 are provided at their lower ends with feet 12 having holes 14 therein so that they may be secured to a floor or other support upon which said feet may rest.

10 16 designates a seat frame which is operably connected to the back frame 18 of the device by suitable means such as tubular hinges 20, as best shown by Fig. 7. Preferably, the seat frame 16 comprises a bottom portion 15 having side flanges 17 and front and rear flanges 19. The back frame comprises a back portion 21 having side flanges 23 and top and bottom flanges 25. The side flanges 23 have lower bifurcated portions 27 to receive the rear ends of the side flanges 17.

20 The tubular hinges 20 have axially disposed bolts 22 each of which is provided at one end with a head 24 and at its opposite end with a nut 26. Each bolt 22 is provided with a bushing 28, Figs. 1 and 7, and a pair of washers 30, 25 which latter are arranged at opposite ends of said bushing 28. The bushings 28 are adapted to rest in any of the superimposed marginal notches 32 in the upright members 4 and prevent the washers 30 from being pressed so tightly 30 against the bifurcated portions 27 as to clamp the same into frictional engagement with the intervening portions of the flanges 17 when the respective nuts 26 are tightened. The bolts 22 and the notches 32 permit the seat and back 35 frames 16 and 18, respectively, to be adjusted to different elevations to suit the convenience of the user of the device. The seat frame 16 is swingable on the hinges 20, so that it may be swung downwardly to the full line position or 40 upwardly to the dotted line position shown by Fig. 3, in order to be out of the way when not in use. The back frame 18 is also swingable on the hinges 20, so that it may be swung forwardly or backwardly as desired. Screws 34 are 45 provided for securing the back frame 18 in different positions. Said screws 34 extend freely through longitudinal slots 36 in the upper portions of the upright members 4 and are adapted to enter any of the threaded holes 38 in the reinforced portions 40 of the side flanges 23 of the back frame 18. The slots 36 permit the screws 34 to move with the back frame 18 when the latter and the seat frame 16 are adjusted to different elevations.

Mechanism is provided for supporting the seat frame 16 for use by an occupant and for lowering said seat frame to the full line position shown by Fig. 3. Said mechanism comprises a pair of pinions 42, oppositely disposed segmental gears 44 spaced apart and formed integral with the side flanges 17 of the seat frame 16, a shaft 48 mounted in bearings 49 and upon which said pinions 42 are loosely mounted, a pair of ratchet wheels 50 fixed upon the shaft 48 and arranged beside the pinions 42, pawls 52 pivotally mounted upon the pinions 42 and coacting with the respective ratchet wheels 50, a spiral gear wheel 54 fixed upon the shaft 48, a spiral gear wheel 56 intermeshing with said spiral gear wheel 54 and fixed upon a shaft 58 mounted in the back frame 18 and provided at its upper end with a knob 60 whereby it may be rotated. The bearings 49 are secured to the flange 25 and the spiral gear wheels 54 and 56 are enclosed in a housing 57 secured to the back frame 18. By rotating the knob 60 in the proper direction the ratchet wheels 50 will rotate the pinions 42 in the direction of the arrow, Fig. 5, through the intermediary of the pawls 52 and the ratchet wheels 50 and thus effect the lowering of the seat frame 16 to any desired point. The seat frame 16 may be quickly swung upwardly to any desired point by grasping the forward portion of said seat frame and pulling upwardly thereon. As the seat frame is swung upwardly the pawls 52 run idly around the respective ratchet wheels 50 and permit the pinions 42 to be freely rotated in a reverse direction to the arrow, Fig. 5, by the segmental gears 44. When the seat frame is released it is prevented from swinging down by the pawls 52 positively engaging the teeth of the ratchet wheels 50 which are held from rotation by the spiral gear wheels 54 and 56.

The device above described and shown by Figs. 1 to 7, inclusive, is well adapted for use on locomotives as the resilient legs 10 permit the device to sway laterally in either direction and thereby reduce to a minimum the ill effects to which the engineer might otherwise be subjected from the swaying of the locomotive when in operation. The ability to swing the seat frame 16 either to the full or dotted line position shown by Fig. 3 adds to the convenience of the device as it enables said seat frame and the cushion (hereinafter described) carried thereby to be adjusted out of the way when the engineer desires, while in a standing posture, to operate the locomotive. In addition to being used on a locomotive the foregoing device may also be used to advantage in other places as hereinbefore pointed out.

The seat and back frames are rendered comfortable for the user by suitable cushioning means shown in the present instance in the form of connected seat and back cushions 62 and 64, embodying coil springs 66 and 68 and supplemental frames 70 and 72, respectively. The seat and back cushions 62 and 64 are removably held in place by lugs 74 and 76 projecting from the front and top flanges 19 and 25, respectively. The lugs 74 overlap the forward end of the supplemental frame 70 and the lugs 76 overlap the upper portion of the frame 72.

In the modified form shown by Fig. 8, the seat and back frames are substantially the same as those best shown by Fig. 1, as is evidenced by corresponding reference numerals with exponents *a*, the chief difference being that the segmental gears 44*a* are formed on the lower ends of the back frame 18*a* instead of on the rear ends of the

seat frame 16. The manually controlled mechanism is also substantially the same, excepting that it is mounted on the seat frame 16*a* instead of the back frame as shown by Fig. 1. The transverse members 6 and 8 and the screws 34 5 are preferably dispensed with, so that the back frame 18*a* may be lowered to a horizontal position if it is desired to convert the device into a bed.

In the modified form shown by Fig. 9 the seat 10 and back frames and the seat and back cushions are substantially the same as those shown by Figs. 1 to 3, inclusive, as is evidenced by corresponding reference numerals with exponents *b*, the main difference being that the back cushion 64*b* is 15 provided with means for preventing its two opposite sides from becoming wrinkled when the front side of said cushion 64*b* is pulled downwardly by the seat cushion 62*b* when the latter is depressed by an occupant sitting thereon. The 20 wrinkle preventing means comprises a pair of stiff rods 80 secured to the opposite sides of the cushion 64*b* by stitching or other suitable means, and tensioning springs 82 secured to said rods 80 and the supplemental frame 72*b*. With the foregoing arrangement it is apparent that when the front portion of the cushion 64*b* is pulled downwardly as above stated the sides of said cushion will be held taut by the rods 80 and the 25 springs 82. A further difference between the 30 cushioning means shown by Fig. 9 and that disclosed by Figs. 2 and 3 resides in woven wire strips 84 which are employed for reinforcing the cloth or other covering of the cushions 62*b* and 64*b*. 35 The strips 84 are also connected to the forward ends of the springs 68*b* by means of clips 86, Fig. 10. The coil springs 68*b* have been omitted from Fig. 9, to avoid confusion with the wires 80 and the tensioning springs 82.

From the foregoing description it is apparent that I have provided devices embodying the advantages above pointed out, and while I have shown several forms of such devices I reserve all rights to such other forms and modifications 45 thereof as properly fall within the spirit and scope of the invention as claimed.

Having thus described my invention, what I claim and desire to secure by Letters Patents, is:

1. A device of the character described comprising a main frame having a pair of upright members with notches spaced one above another, a seat frame and a back frame projecting between said upright members, hinge means operably connecting said seat and back frames including members extending through said frames and adapted to rest in any of said notches and thereby support the seat and back frames at different elevations, and means on the upright members and the back frame cooperating with the hinge members in supporting the seat and back frames at different elevations.

2. A device of the character described comprising a main frame having a pair of upright members with marginal notches and longitudinal slots, a seat frame and a back frame projecting between said upright members, hinge means operably connecting said seat and back frames including members extending through said frames and adapted to rest in any of said notches and thereby support the seat and back frames at different elevations, and elements extending freely through the longitudinal slots in said upright members and removably engaging said back 75

- frame to prevent accidental forward or backward movement thereof.
3. A device of the character described comprising a main frame having a pair of upright members with marginal notches and longitudinal slots, a seat frame and a back frame projecting between said upright members, said back frame having a plurality of holes arranged side by side in its upper side portions, hinge means operably connecting said seat and back frames, including members extending through said frames and adapted to rest in any of said notches and thereby support the seat and back frames at different elevations, and elements extending freely through the longitudinal slots in said upright members and adapted to be threaded into any of said holes to secure the back frame in different positions to which it may be adjusted through the intermediary of the hinges.
- 20 4. A device of the character described comprising a main frame having a pair of upright members with marginal notches spaced one above the other, a seat frame and a back frame projecting between said upright members, hinge means operably connecting said seat and back frames in-

cluding members projecting through said frames and adapted to rest in any of said notches and thereby support the seat and back frames at different elevations, a bushing on each hinge member where it is adapted to rest in any of the associated notches in the upright members, a washer at each end of each bushing, and means on each hinge member for drawing the washers against the ends of the respective bushing.

5. A device of the character described comprising a main frame having a pair of upright members with marginal notches, a seat frame and a back frame projecting between said upright members, hinge means operably connecting said seat and back frames and including members extending through said frames and adapted to rest in any of said notches and thereby support the seat and the back frames at different elevations, means cooperating with the hinge members in supporting the seat and back frames at the different elevations, and cooperating means on the seat and back frames for swinging said seat frame up or down on the hinges.

JOHN M. DORTON. 25
